United States Patent Office

Des. 179,633
Patented Feb. 5, 1957

179,633

BOWLING SCORE TABLE

George G. Fox, Chicago, Ill., assignor to American Machine & Foundry Company, a corporation of New Jersey

Application May 4, 1956, Serial No. 41,349

Term of patent 14 years

(Cl. D34—5)

The single figure is a perspective view of a bowling score table embodying my new design.

I claim:

The ornamental design for a bowling score table, as shown.
